UNITED STATES PATENT OFFICE.

ANDREW O'BRIEN, OF NEW YORK, N. Y.

IRONING BOARD.

Application filed March 27, 1922. Serial No. 546,957.

To all whom it may concern:

Be it known that I, ANDREW O'BRIEN, a citizen of the United States, residing in the borough of Manhattan, city, county, and 5 State of New York, have invented certain new and useful Improvements in Ironing Boards, of which the following is a specification, reference being had to the accompanying drawings, forming a part thereof.

10 My invention relates to improvements in ironing boards and particularly to ironing boards of the folding type which are provided with collapsible supports.

Among the objects of my invention are 15 the provision in an ironing board of the character specified, of collapsible supports adapted to fold against the board and to lie flat thereagainst, so that the folded structure shall occupy a minimum of space 20 when stored; the provision of supports such that, when, unfolded, a maximum of rigidity is attained by their mutual bracing; the further provision of means adapted to permit of the adjustability of a plurality of the 25 supporting members relatively to each other, whereby a tripod base results, affording a maximum of stability; and also, the provision of a spring catch adapted when locked to hold all the supports in fixed relation, 30 and further adapted to be released by a finger-pull conveniently located beneath and at the end of the board. Further objects are simplicity and strength of construction; lightness, compactness and fewness of parts; 35 ease of operation in setting up and taking down; strength, rigidity and stability in operation; and finally cheapness and economy of manufacturing cost.

With the foregoing and hereinafter 40 recited objects in view, my invention consists in the arrangement of parts substantially as shown in the drawings, in which is shown the preferred structural embodiment of my improvements in ironing boards, and 45 in which Figure 1 is a side view in vertical elevation of said board as extended for use; Figure 2 is an end view looking from the left side of Figure 1; Figure 3 is a plan view of the under side of the collapsed 50 board; and Figure 4 is a detail of the adjustable spreader, taken upon the section line 4-4 of Figure 2.

Like reference numerals indicate the same parts throughout the several views, in which 55 1 is the ironing board or table; 2 and 3 are

supports or legs adapted to turn upon the bolt 4 which is secured by blocks 5 and 6 to the under-side of the board 1, these blocks being held to said board by screws. The bolt 4 extends through holes 7 and 8 in the 60 supports 2 and 3, respectively, these holes being flared at the outer sides to permit the feet 9 and 10 of the supports to be moved away from each other, for which purpose the upper ends of the supports are cut away 65 at their inner and opposing sides, 11 and 12, so that as the feet are spread apart these sides contact with and are supported by the blocks 5 and 6, respectively. The bolt 4 has a head at one end and a nut at the other. 70 The feet 9 and 10 are connected by the braces 13 and 14 which are pivoted at their outer ends to the supports 2 and 3, respectively, and slide upon each other through the guide clamp 15, the outward motion of either being limited by the stops 16. The clamp 15 has a thumb screw 17 adapted to hold the braces 13 and 14 tightly together in their 75 adjusted position. Upon the bolt 4 is also pivoted a diagonal support composed of 80 two parts, 18 and 19, spaced apart at their pivoted ends and held together at their opposite or foot end by a transverse screw, a metal plate 20 being attached preferably to this foot for strength and to prevent slipping. 21 is a diagonal support, pivoted at 85 22 between the parts 18 and 19, and attached at its lower end by a pin 23 fixed to the block of the clamp 15, the pin 23 extending through the slot 24 in the support 21, the upper end 25 of said support 21 being chamfered to seat against the under surface of the board 1 and to engage between it and the stop 26. A notch 27 in said support 21 is 90 adapted to receive the tongue 28 of a spring latch 29, the said latch tongue having a rearward extension 30 terminated by a finger pull 31, conveniently located at the end of the board and below its top.

The method of operation is as follows: Assuming the board erected as shown in Fig. 1, retraction of the latch permits the diagonal support 21 to swing upon its pivot 22 and to be received between the parts 18 and 19 of the other diagonal support as the latter is raised until it is in the plane of the supports 2 and 3, when all supports may be 100 swung upon the bolt 4 against the board 1, and will lie snugly thereagainst.

The board, with supports collapsed as 110

shown in Figure 3, is opened by lifting the foot 20 to a vertical position, all supports rising therewith. The supports 2 and 3 being thus maintained in this position, the 5 diagonals fall forward into place automatically upon manual release, the end 25 of the support 21 engaging the stop 26 and becoming latched by its own pressure. The board is then stood upon its supports, and 10 the legs 2 and 3 are spread apart, the clamp 15 being tightened when the desired divergence therebetween is attained.

I am aware that prior patents disclose ironing boards and tables having vertical 15 and diagonal supports adapted to collapse, but I believe that my improvement there-over by which one diagonal support of sub-stantially triangular form nests within the other diagonal support and both nest with- 20 in the vertical supports, all said supports, when collapsed and so nested lying flat against said board and presenting a surface parallel to the board, is new; also the par-ticular features of advantage and utility are 25 new, namely, that said supports are opened up by a single manual operation and when extended, become rigidly fixed relatively to each other semi-automatically by the inner diagonal member snapping into place and 30 engaging the catch which locks said mem-ber and, through it, holds all said supports in rigid relation; and finally, that by the provisions of a convenient manual release, the supports are unlocked and so arranged

that a single operation causes them to fold 35 and nest semi-automatically, as described.

Having thus described my improvement, I claim as new:

The combination of an ironing board with collapsible supports therefor, comprising a diagonal support pivoted between two members adapted to constitute a second diagonal support and adapted to nest be-tween said members when the supports are collapsed; a pair of vertical supports piv- 40 oted to a rod beneath said board, said rod constituting the sole attachment between said board and its supports, the second di-agonal support being also pivoted upon said rod; an adjustable brace between said 45 vertical supports, whereby when extended said supports may be moved out of the per-pendicular and afford, with the second di-agonal support, a tripod base for said board, the said vertical supports being adapted to 50 receive the diagonal supports when col-lapsed and to nest same flat against said board; a sliding connection between one end of said first-named diagonal support and said adjustable brace, the other end of said 55 diagonal support being formed to engage a stop upon the under-surface of said board and a spring latch upon said surface adapt-ed to lock the end of said diagonal support against said stop, said locking action serv- 60 ing to hold all supports rigidly in their ex-tended positions.

ANDREW O'BRIEN.
